UNITED STATES PATENT OFFICE.

CARL EUGENE SIMS, OF EASTLAND, TEXAS.

OIL SPRAY.

Original application filed March 15, 1923, Serial No. 625,360. Divided and this application filed June 7, 1924. Serial No. 718,609. Renewed December 6, 1927.

This invention relates to an improvement in oil sprays especially adapted for use in conjunction with douches of the type forming the subject-matter of my co-pending application filed March 15, 1923, Serial No. 625,360, of which the present application is a division.

The object of the invention is to provide an oil spray of this character adapted to apply the proper amount of oil for the treatment adapted to the particular case.

A further object is to provide a device of this character and which is of simple and durable construction, reliable in operation, easily controlled and manipulated and comparatively inexpensive to manufacture.

Other objects and advantages of the invention reside in certain novel features of the construction, combination and arrangement of parts which will be hereinafter more fully described and particularly pointed out in the appended claim, reference being had to the accompanying drawings forming part of this specification, and in which:

Figure 1 is a view, partly in section and partly in elevation, showing the oil spray constituting the present invention organized with a douche and speculum; and

Figure 2 is a view in section on line 2—2 of Figure 1.

Referring to the drawings, the numeral 10 designates the douche and speculum forming the subject-matter of my co-pending application filed March 15, 1923, Serial No. 625,360.

The oil spray which constitutes the present invention includes a barrel 50 of cylindrical form which is removably mounted in the bearing bushing 45 of the douche and speculum. The upper end of the barrel 50 is provided with a perforated head or cap 51 having threaded connection with the interior of the body of the barrel and the lower end of the barrel may be closed by a head 52 (although this head 52 may be omitted if desired). A plunger 55 is slidably fitted in the barrel 50 and is actuated by a plunger rod 56 which extends exteriorly of the barrel and terminates in a knob 57. The plunger rod 56 operates through a bracket 58 fixed to the barrel at the lower end thereof.

In order to provide for the measuring of a charge of oil the rod 56 may be provided with a number of annular notches 59 cooperable with a spring detent 60 fixed to the head 52 and biased so as to spring into the notches 59 when the same are brought into alignment with the detent. The detent is provided with a finger piece 61 to provide for the release of the same.

I claim:

An oil spray including a barrel, a plunger operating in said barrel, a plunger rod connected with the plunger and extending exteriorly of the barrel, said plunger rod having a series of annular notches and a laterally flexible spring detent carried by the barrel and cooperable with the notches.

CARL EUGENE SIMS.
